ADVERTISING DISPLAY OR SIMILAR ARTICLE

Elliott R. Loew, Great Neck, N. Y.

Application July 3, 1953, Serial No. 25,787

Term of patent 3½ years

(Cl. D80—1)

To all whom it may concern:

Be it known that I, Elliott R. Loew, a citizen of the United States and a resident of Great Neck, New York, have invented a new, original, and ornamental Design for an Advertising Display or Similar Article, of which the following is a specification, reference being had to the accompanying drawing, forming a part hereof, in which:

Figure 1 is a perspective view of an advertising display or similar article, showing my new design;

I claim:

The ornamental design for an advertising display or similar article, as shown.

ELLIOTT R. LOEW.
